SUBSTATION TELEPHONE APPARATUS

Louis Jean Joseph Schreiber, Antwerp, Belgium,
assignor to Western Electric Company, Incorporated,
New York, N. Y., a corporation of New York

Application March 20, 1937, Serial No. 131,979
In Belgium June 17, 1936

5 Claims. (Cl. 179—158)

This invention relates to telephone subsets and, more particularly, to attachments or adaptor boxes therefor.

The object of the invention is to provide an attachment which comprises a locking push-button, key, or the like, and is readily attachable and detachable from a standard subset in such a way that the locking key can be unlocked by the depression of the switchhook.

10 This object is attained by providing a flexible transmission cable connection between the subset and the locking device in the adaptor box.

Such a device is of value for adapting ordinary subsets for special purposes such as for connection to two lines with provision for holding on one line while calling on the other line.

20 An adaptor box according to the invention and its connection to a desk-set will be described below with reference to the accompanying drawing;

Fig. 1 of which shows the desk-set and box in side elevation with the covers partly cut away to expose the novel mechanism;

Fig. 2 shows the method of mounting the end of 25 the flexible connection in the desk-set on a larger scale.

The adaptor box 2 carries a push-button 3 on a vertical stem 4 journaled in a stirrup 7 within the box. The stem 4 carries a locking member 5 30 of inverted cone shape, and a compression spring 6 between the lower arm of stirrup 7 and the bottom of locking member 5. The stirrup 7 also carries a pivoted two armed locking lever 8, 9, which is biased by a spring 16 so as to tend to rotate 35 in a clockwise direction.

The stirrup 7 is mounted on a vertical support 11 in which is fixed one end of the outer flexible tube 12 of a "Bowden" wire transmission cable. This tube 12 is led out through the side of the box. 40 Through the tube passes the transmission wire 13 carrying at the end inside the box 2 a plunger 10, impinging on the bottom end of the lower arm 9 of the locking lever.

When such an attachment comprising the box 45 2 with the "Bowden" wire connection is to be attached to a desk-set 1, a bracket 15 is fixed to the base of the desk-set, which is perforated for the passage of the cable 12, 13. The end of the flexible tube 12 is fixed in the bracket 15 which is 50 so positioned that a plunger 14 attached to the end of the transmission wire 13 can be operated by the switchhook assembly.

In the position shown, the microtelephone or telephone handset is off the switchhook, and the 55 button 3 is locked in depressed position by the

locking lever 8, 9. If, now, the switchhook is depressed, the plunger 14 is forced downwards causing the wire 13 to force the plunger 10 in the box 2 to the right. This movement of plunger 10 rotates locking lever 8, 9 anti-clockwise against 5 spring 16 so that the lever arm 8 releases the member 5 and the stem 4 and the button 3 are raised to normal position by spring 6.

If now the switchhook is raised, the spring 16 biasing locking lever 8, 9 in the box 2, takes control, turns the lever 8, 9 into locking position and forces plunger 10 and wire 13 to the left so that plunger 14 again rises to the position shown in the drawing. When the button 3 is depressed, lever arm 8 engages the member 5 and locks the 15 button 3 in depressed position.

What is claimed is:

1. A hand telephone support comprising a base portion, a cradle portion to receive a hand telephone, a circuit-controlling plunger member to 20 be depressed by the hand telephone when placed on the cradle portion and to be movable upwardly upon removal of the hand telephone, and means for locking the plunger member in its upward position, said means comprising a flexible 25 cable attached at one end to said plunger member, and spring-controlled means at the other end of said cable.

2. An attachment for a telephone instrument support having a plunger member operable upon 30 removal or replacement of the telephone instrument on the support, comprising spring-controlled means, and a motion-transmission wire engaged at one end by said spring means for attachment to and movement with the plunger 35 member.

3. An attachment for a telephone instrument support having a plunger member operable upon removal or replacement of the telephone instrument on the support, comprising means for locking the plunger in position upon removal of the instrument, said means comprising a flexible cable attached at one end to said member, spring-controlled means at the other end of said cable, and a manually operable member associated with said 45 spring-controlled means.

4. An attachment for a telephone instrument support having a plunger member operable upon removal or replacement of the telephone instrument, comprising means for locking the 50 plunger in position upon removal of the instrument, said means comprising a motion-transmission wire for attachment at one end to said plunger, and spring-controlled means at the other end of said wire. 55

5. An attachment for a telephone instrument support having a plunger member operable upon removal or replacement of the telephone instrument, comprising a casing, a bracket within said casing; a lever, a push-button and spring means on said bracket, and a motion-transmission wire

having one end within said casing engaging the lever and another end outside of said casing for attachment to the plunger member of said instrument support.

LOUIS JEAN JOSEPH SCHREIBER.
